US0D1098908S

(12) **United States Design Patent** (10) Patent No.: **US D1,098,908 S**
(45) Date of Patent: ** Oct. 21, 2025

(54) **PACKAGING**

(71) Applicant: **Apple Inc.**, Cupertino, CA (US)

(72) Inventors: **Megan J. Burmeister**, Menlo Park, CA (US); **Shannon M. McGrath**, Los Angeles, CA (US); **Teresa Y. Yen**, Arcadia, CA (US); **Kelsey M. Kiefiuk**, Palm Desert, CA (US)

(73) Assignee: **Apple Inc.**, Cupertino, CA (US)

(**) Term: **15 Years**

(21) Appl. No.: **29/879,940**

(22) Filed: **Jul. 14, 2023**

(51) LOC (15) Cl. **09-03**

(52) U.S. Cl.

USPC **D9/415**

(57) **CLAIM**

The ornamental design for packaging as shown and described.

DESCRIPTION

FIG. 1 is a top front isometric view of packaging showing the claimed design;

FIG. 2 is a bottom rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The dashed broken lines in the figures show portions of the packaging that form no part of the claimed design.
